JOINT FOR FRAME MEMBERS.

1,179,940.

Specification of Letters Patent. Patented Apr. 18, 1916.

Application filed February 27, 1915. Serial No. 11,055.

To all whom it may concern:

Be it known that we, JOSEPH F. LAMB and HEMAN C. MAGARGAL, citizens of the United States, and residents of New Britain, in the county of Hartford and State of Connecticut, have invented certain new and useful Improvements in Joints for Frame Members, of which the following is a specification.

10 This invention relates to a frame within which an electric heater, for instance in the form of coiled resistance wire, is mounted and supported. The frames may be variously shaped, and sized to meet different conditions.

15 The object of the invention is to provide such a frame which can be easily and cheaply manufactured and the parts of which can be securely connected together and yet be readily separable in order that one part which may have been damaged can be replaced by another. Not only does the construction permit of such replacement, but it also facilitates and cheapens the assembly 25 of the device.

The portion of the frame chosen for illustration is such as is commonly used in what is known as an electrical grill.

Figure 1 is a plan view of a portion of 30 such a frame. Fig. 2 an end view, the side members of the frame being in section. Fig. 3 is a side view of a portion of one of the side members of the frame.

In the drawings, *a*, *a*, denote the side members of the frame, and *b*, *b*, the cross bars secured at their ends to the side members. The invention is found in the method of securing the cross bars to the side members. The side members are longitudinally channeled by offsetting the central portion, as indicated at 2, providing edge flanges 3, 3. In the offset or channeled portion are elongated slots 4, and alined notches 5, 5, are formed in the edge flanges 3, about opposite 45 site the center of the elongated slot 4. Centrally at the ends of the cross bars are formed T-headed projections 10, the length of the T head being such that it will fit into and pass through the elongated slots 4. 50 At either side of the shank of this T-headed projection the ends of the bar are straight, as indicated at 11, 11, and for such a distance that when the bar is turned so that its width is at right angles to the side mem-

bers *a*, *a*, they will snap into and interlock 55 with the notches 5, 5, of the edge flange. The corners of the bar are slabbed off on an incline, as indicated at 13.

To assemble the bar with the side members it is only necessary to insert the 60 T-headed projection through the elongated opening 4, and then turn the bar. The spring of the metal of the side members is sufficient to allow the cross bar to be turned until the straight parts of the ends come 65 opposite the notches 5, 5, at which time the bar becomes interlocked with the side members, as clearly indicated in Fig. 2, providing a very rigid connection between the bar and the side members, and at the same time 70 one which can be easily made or broken by a mere rotation of the cross bar.

The invention has been described in regard to the embodiment illustrated in the drawings, but the language used is not language of limitation, but merely of description. Furthermore it is clear that the invention is not to be limited to the shape of the frame or of its separate members.

We claim as our invention—

1. In a device of the character described, a frame member comprising edge flanges and a central offset portion having an elongated slot therein and alined notches in the edge flanges, a transverse member provided at its 85 end with a T-headed projection, the head of which is adapted to pass through the elongated slot, and the stem rotatable within said slot, flat surfaces at either side of said stem, adapted to enter and interlock with 90 said notches.

2. In a device of the character described, a frame member provided with edge flanges and a central depressed portion having alined notches in the edge flanges and an 95 elongated slot in the offset portion in line with said notches, a second frame member arranged at an angle to the first, a T-headed projection at the end thereof adapted to pass through the elongated slot and by the 100 rotation of said member to be interlocked with the first mentioned frame member, the length of the stem of said projection being less than the distance from the outside of said offset portion to the opposite side of 105 the edge flanges.

3. In a device of the character described, a channeled frame member having an elong-

gated slot in its central portion, a cross bar provided with a T-headed projection at its end adapted to pass through said elongated slot, its stem being shorter than the depth 5 of said channel, the said cross bar being rotatable to bring it into normal position, and means at the edges of said channeled member adapted to engage the ends of said cross bar when it is rotated into normal position.

10 4. In a device of the character described, a channeled member of slightly resilient material having an elongated slot arranged centrally of said channeled member and notches in the edges thereof, a cross bar 15 having a T-headed projection at its end adapted to pass through the elongated slot and permit rotation of the cross bar, flat portions at either side of the stem of said T-headed projection adapted upon the rotation of said cross bar to temporarily dis-

20

place the resilient edge portions of the channeled member to interlock with the notches in the edges thereof.

5. In a device of the character described, a channeled frame member having an elongated slot at its center and notches in its edges in line with said slot, a cross bar the surface of which is arranged transversely of the channeled member, a T-headed projection at the end of said cross bar extending through the slot and with its head arranged transversely to said channeled member, and engaging portions at either side of the stem of said projection lying in the notches.
